H. K. HYRUP

EXTERNAL PIPE THREAD CLEANER AND CHASER

Filed Nov. 2, 1925

20 INVENTOR

Hans K. Hyrup.

By Martin P. Smith, Atty.

UNITED STATES PATENT OFFICE.

HANS K. HYRUP, OF LOS ANGELES, CALIFORNIA.

EXTERNAL PIPE-THREAD CLEANER AND CHASER.

Application filed November 2, 1925. Serial No. 66,215.

My invention relates to a pipe thread cleaner and chaser of the particular type disclosed in my co-pending application for U. S. Letters Patent filed September 25, 1924, Serial Number 73,982, the principal objects of my present invention being to generally improve upon and simplify the construction of the device disclosed in my aforesaid application, as well as other existing forms of pipe thread cleaners and chasers, to provide a tool of the character referred to that is semi-automatic in its adjustment to pipes or tubes of different diameters and, further, to provide a pipe thread cleaner and chaser that is relatively simple in construction, capable of being easily and cheaply produced and which will be very effective in performing its intended functions.

With the foregoing and other objects in view, my invention consists in certain novel features of construction and arrangements of parts that will be hereinafter more fully described and claimed and illustrated in the accompanying drawings in which—

Fig. 1 is a top plan view of a pipe thread cleaner and chaser of my improved construction.

Figs. 2 and 3 are side elevational views of the tool and showing same applied to pipes or tubes of different diameters.

Fig. 4 is an enlarged cross section taken on the line 4—4 of Fig. 2.

Referring by numerals to the accompanying drawing which illustrates a practical embodiment of my invention, 10 designates a short horizontally disposed arm, at the forward end of which is formed a loop or socket 11 for a thread chasing bit 12. This bit is preferably formed of hardened metal and its upper and lower ends are beveled and provided with V-shaped teeth 13, that correspond with standard pipe threads.

Formed integral with the rear end of arm 10 is a pair of vertically disposed plates 14 that are spaced apart for the reception of the vertically disposed leg 15 of an L-shaped jaw 16 and for the head portion 17 of a handle 18.

Head 17 is pivoted to plates 14 by a pin or

bolt 19 and depending from the inner portion of the head is a lug 20 that is adapted to bear against the adjacent edge of leg 15 and thereby clamp the latter against the end of arm 10 while the tool is in service.

To lock the head 17 and handle 18 in position for use, a set screw 21 passes through one of the plates 14 and bears against the corresponding side face of head 17.

Formed in the inner face of leg 15 of jaw 16 and near the upper end thereof is a series of notches 22, any one of which is adapted to receive a pin or bolt 23, that is seated in plates 14.

Pivoted secured by means of a pin or bolt 24 to the lower portion of L-shaped member 16 is the rear end of a bifurcated arm 25 that overlies the horizontal arm of said L-shaped member and journalled at the forward end of said arm 25 is a horizontally disposed roller 26 of brass or analogous material that occupies a position directly beneath the thread chaser 12.

Screw-seated in the end of the horizontal arm of L-shaped member 16 is an adjusting screw 27, the upper end of which bears against the underside of arm 25.

Arranged on the sides of plates 14 and pivotally connected to the lower portion of the vertical leg 15 of the L-shaped member 16 are plates 28 in the upper portions of which are formed arcuate slots 29 through which pass the end portions of a pin 30 and which latter is seated in the forward portion of the plates 14 a short distance below pin 23.

Seated in the forward portions of plates 28 is a pin 31 upon which is journalled a bearing roller 32 of brass or analogous material that is adapted to bear on the periphery of the pipe or tube on which the tool is used.

The shape of the slots 29 and the relation of pin 30 to the point of pivotal connection between the plates 28 and member 16 are such that as L-shaped member 16 is moved upward between the plates 14, the plates 28 that carry bearing roller 32 will substantially move forward the proper distance so that

roller 32 has bearing on the pipe or tube upon which the tool is used.

The vertical position of bearing roller 26 is adjusted by manipulation of screw 27, whereas, the position of roller 32 is determined automatically and in keeping with the position of L-shaped member 16 relative to the fixed jaw or member of the tool and which latter comprises arm 10 and plates 14. Thus, when the tool is applied to a pipe for the purpose of cleaning or chasing the threads thereon, said pipe is supported at separated points by the rollers 26 and 32 with said roller 26 in engagement with the pipe at a point approximately diametrically opposite from the bearing point of the chasing bit 12.

In adjusting the tool to pipes or tubes of different diameters, set screw 21 is unscrewed to release head 17 after which the handle 18 is swung upward into the position shown by dotted lines Fig. 3, thereby enabling the vertical leg 15 of the L-shaped member to be moved horizontally a sufficient distance to effect a disengagement between the pin or bolt 23 and notch 22 in which said pin or bolt has been seated.

Leg 15 is now moved vertically or into position so as to accommodate the pipe between roller 26 and bit 12, after which leg 15 is moved forward so that pin or bolt 23 reengages in one of the notches 22. Handle 18 is now swung downward until lug 20 bears against leg 15 thereby locking said leg in engagement with the pin 23, and set screw 21 is now tightened to lock the head 17 of the handle in position between plates 14.

It will be understood that, as member 16 is elevated, or moved toward arm 10 for the accommodation of the smaller sizes of pipes, the arcuate slots 29 cooperate with the ends of pins 30, will move the plates 28 forwardly so as to automatically bring roller 32 into bearing engagement with the pipe to which the tool is applied.

Obviously, as member 16 is moved downward for the accommodation of pipes of larger diameter, plates 28 carrying roller 32, will be moved toward vertical leg 15 of member 16 and thus position roller 32, so as to engage the periphery of the larger pipes.

In the use of my improved tool after the same has been properly applied to the thread portion of a pipe, the tool is swung around the pipe by pull or pressure applied to handle 18 and the engagement of the teeth of bit 12 in the grooves of the thread will quickly and effectively clean and straighten the latter, thus accomplishing the desired results.

The operation of my improved tools is greatly facilitated and rendered more efficient by the arrangement of the two bearing rollers that engage the periphery at points slightly greater than 90° apart and with the

lower one of the two rollers disposed approximately 180° from the bit or thread cleaning and chasing member.

Thus it will be seen that I have provided a pipe thread cleaning and chasing tool that is relatively simple in construction, capable of being easily and cheaply produced and semi-automatic in adjustment to pipes or tubes of different sizes, and which tool may be advantageously and economically employed in the cleaning and chasing of threads on tubes and pipes and particularly those used in and around oil wells and the like.

It will be readily understood that minor changes in the size, form and construction of the various parts of my improved pipe thread cleaner and chaser may be made and substituted for those herein shown and described without departing from the spirit of the invention, the scope of which is set forth in the appended claims.

I claim as my invention:

1. In a pipe thread cleaner and chaser, a pair of adjustably associated jaws, a bearing roller carried by one jaw, a chasing bit carried by the other jaw, a pair of links pivotally connected to one of the jaws and connected to the other jaw so as to move toward the bearing roller when the two jaws are moved toward each other, a bearing roller carried by said links and a handle pivotally connected to one of said jaws for manipulating the tool and for locking the two jaws to each other in differently adjusted positions.

2. In a pipe thread cleaner and chaser, a pair of adjustably associated jaws, a chasing bit carried by one of said jaws, an arm pivotally and adjustably mounted on the other jaw, a pair of links pivotally mounted on the jaw that carries the pivotally and adjustably mounted arm, a bearing roller carried by said links and said links bearing upon the other one of the jaws so that said links and the bearing roller carried thereby are moved toward the first mentioned bearing roller when the jaws are adjusted toward each other.

3. In a pipe thread cleaner and chaser, a pair of adjustably associated jaws, a bearing roller carried by one jaw, a chasing bit carried by the other jaw, a pair of links pivotally connected to one of the jaws, a bearing roller carried by said links and connections between said links and the bit carrying jaw, whereby the roller carrying links are swung upon their axes as the jaws are moved toward or away from each other.

4. In a pipe thread cleaner and chaser, a pair of adjustably associated jaws, a pair of links pivotally connected to one of the jaws, a bearing roller carried by said links, connections between said links and the bit carrying jaw, whereby the roller carrying links are swung upon their axes as the jaws are moved toward or away from each other.

and means associated with the jaws for locking the same to each other in differently adjusted positions.

5. In a pipe thread cleaner and chaser, a pair of adjustably associated jaws, a chasing bit carried by one of said jaws, a bearing roller adjustably mounted on the jaw and located so that it will engage the pipe to

which the tool is applied at a point diametrically opposite the bearing point of the bit 10 upon the engaged pipe, links pivotally mounted on one of said jaws and having pin and slot connections with the other jaw and a bearing roller carried by said links.

In testimony whereof I affix my signature.

HANS K. HYRUP.
